[57] CLAIM

The ornamental design for a surgical console for ophthalmic surgery, as shown and described.

DESCRIPTION

FIG. 1 is a perspective view showing the upper, front and right side view of the new design for a surgical console for ophthalmic surgery;

FIG. 2 is a perspective view showing the upper, rear and left side view of the new design for a surgical console for ophthalmic surgery;

FIG. 3 is a perspective view similar to FIG. 1 with the telescoping swing arm of a tool tray in the extended position;

FIG. 4 is a perspective view showing the upper, rear and left side view of the surgical console for ophthalmic surgery illustrated in FIG. 3;

FIG. 5 is a perspective view similar to FIG. 3 with the extended swing arm rotated to a forwardly extending position; and,

FIG. 6 is a perspective view similar to FIG. 1 with the information and control screen rotated to the right side.

UNITED STATES PATENT AND TRADEMARK OFFICE
Certificate

Patent No. Des. 352,106

Patented: November 1, 1994

On petition requesting issuance of a certificate for correction of inventorship pursuant to 35 U. S. C. 256, it has been found that the above-identified patent, through error and without deceptive intent, improperly sets forth the inventorship.

Accordingly, it is hereby certified that the correct inventorship of this patent is: Douglas M. Fanney, San Clemente, Calif.; Long O. Nguyen, Corona, Calif.; Robert Peterson, Rancho Santa Margarita, Calif.; Miles A. Conklin, St. Louis, Mo.; Paul C. Pynckel, Santa Anna, Calif.; Kenneth Mori, Los Angeles, Calif.; Douglas M. Patton, Irvine, Calif. and Joaquin Wolff, Colleyville, Tex.

Signed and Sealed this Seventh Day of October, 1997.
